UNITED STATES PATENT OFFICE.

CLARK J. WINSLOW, OF APPLETON, MINNESOTA.

COMBINATION-LOCK SWITCH.

1,257,059.

Specification of Letters Patent. Patented Feb. 19, 1918.

Application filed April 7, 1915. Serial No. 19,716.

To all whom it may concern:

Be it known that I, CLARK J. WINSLOW, a citizen of the United States, residing at Appleton, in the county of Swift and State 5 of Minnesota, have invented certain new and useful Improvements in Combination-Lock Switches; and I do hereby declare the following to be a full, clear, and exact description of the invention, such as will enable others skilled in the art to which it 10 pertains to make and use the same.

This invention relates to combination locks, and the primary object of the invention is to provide a combination lock embodying a plurality of dials for controlling the passage of electrical current from a battery or magneto to the spark plugs of an ordinary internal combustion engine, for preventing the malicious operation of an automobile or like vehicle.

Another object of this invention is to provide a plurality of stationary dials which are formed of a plurality of segments insulated from each other, and to connect certain of said segments to a spark plug of an internal combustion engine, for controlling the passage of a current of electricity therethrough, and also to provide a pair of movable dials and contact arms, which arms are 25 electrically connected to a suitable electrical supply source and are provided for engagement with the dial segments connected to the spark plugs upon the positioning of the rotary dial in the proper combination.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the 45 several views, and in which:—

Figure 1 is a plan view of the improved combination lock,

Fig. 2 is a diagrammatic view of the lock, and

Fig. 3 is a vertical section through one of the sets of dials used in the lock.

Referring more particularly to the drawing, 50 1 designates a supporting plate for attachment to the dashboard of an automobile

or like vehicle, which plate has dials 2 and 3 carried thereby. The dials 2 and 3 carry 55 a plurality of segments 4, which are constructed of electrical conductive material and are insulated from each other by insulation strips 5. The dial 2 carries an even 60 number of segments 4, while the dial 3 carries an odd number of segments. One of the electrical conductive segments 4 such as 4^b which is carried by the dial 2 is electrically connected to a pivoted arm or contact 65 7 of a cut-out 8. The cut-out 8 embodies a stationary contact 9. The stationary contact 9 is connected by means of an electrical conductor 11 to one pole of a battery, magneto or the like 12, and the opposite pole of the 70 battery or magneto 12 is connected by means of an electrical conductor 13 to an arm 14, which is constructed of conductive material and is pivotally carried by the apex of a U-shaped bracket 14'. The U-shaped bracket 75 14' is connected to the lower end of a sleeve 16 which is secured to a hollow shaft 17 that extends above the central axis of the dial 3.

To each of the dials 22 and extending therefrom are secured the hollow shafts 17, 80 upon the lower ends of which are mounted sleeves 16. The sleeves 16 are constructed of insulating material and have contact arms 15 pivotally connected thereto and extending beneath the open end of the hollow 85 shafts. The U-shaped bracket 14' is constructed of conducting material, and permits of the passing of an electrical current from the wire 13, through the arm 14 and into the pivoted arm 15. The pivoted arm 15 90 has a spiral spring 15' secured thereto, which is connected to one arm of the U-shaped bracket 14'. A rod 18 extends upwardly through the hollow shaft 17 and has a head 95 19 formed upon its upper end, which projects out of the head 20, which is formed upon the rotary dial 23. The rod 18 engages an insulating plate 21 which is formed in the end of the lever 15 which projects beneath the end of the shaft 17 and is provided 100 for rocking the arm or lever 15 upon its pivotal connection with the sleeve 16. The shaft 17 is carried by the stationary dial 22, and the dial is curved, as is clearly shown in Fig. 3 of the drawings, forming a housing 105 for the dial 3 and the pivoted contact arms 15. The dial 22 is graduated in accordance with the segments 4 formed upon the dial 3.

The shaft 17 has a rotary dial 23 carried thereby outwardly of the dial 22, which rotary dial is graduated in accordance with the stationary dial 22. The dials 2 and 3 5 are alike throughout.

The contact arm 15, which is carried by the dial 2 is electrically connected, by means of an electrical conductor 28 to a spark plug 29, which spark plug may be carried by an 10 internal combustion engine of an automobile or the like. The opposite pole of the spark plug 29, from the one to which the contact 15 is connected, is electrically connected by means of a conductor 30 to one of 15 the segments 4 of the dial 3, which segment will be hereinafter referred to as 4^a.

In the operation of the improved combination lock for controlling the passage of an electrical current to the spark plug 29, the 20 contacts 4^b and 4^a may be any one of the contacts 4 which are carried by the dials 2 and 3, this feature being regulated by the desires of the person using the combination lock.

25 When it is desired to close an electrical circuit, through the electrical supply source 12 and the spark plug 29, the cut-out 8 is operated for moving the pivoted contact 7 into engagement with the permanent contact 9, which will close a circuit through the cut-out 8 and electrically connect the segment 4^b to the electrical supply source 12. Before the dials 23 are rotated, which consequently rotates the sleeves or hollow shafts 30 35 17, the rods 18 are forced downwardly, for moving the contact levers 15 upon their pivotal points and out of engagement with the dials 2 and 3. The dials 23 are then rotated until the graduations formed thereon are positioned in alinement with the proper 40 designations formed upon the dials 22, which indicates the combination of the lock, or that the segments of the dials 2 and 3 that are electrically connected to the various other parts of the lock are beneath the arms 45 15, at which time the release of the pressure upon the pins 18 will permit the contact arms 15 to fall upon the segments 4^a and 4^b.

Copies of this patent may be obtained for five cents each, by addressing the "Commissioner of Patents, Washington, D. C."

which closes a circuit through the cut-out 8, the segments 4^a and 4^b, the contact arms 15, 50 and the spark plug 29 for permitting of the operation of the latter.

From the foregoing description taken in connection with the accompanying drawings the advantages of construction and of the 55 method of operation of the improved combination lock switch will be readily apparent to those skilled in the art to which this invention appertains, and while in the foregoing description, the principle of the operation of this invention has been described together with various features of construction, it is to be understood that certain minor features of construction, combination and arrangement of parts may be altered to suit 60 practical conditions provided such alterations are comprehended within the scope of what is claimed.

What is claimed is:—

In a combination lock switch, a dial constructed of a plurality of segments, the alternate segments of said dial formed of conductive and non-conductive material, a stationary dial positioned above said first named dial and being graduated correspondingly to the segments of the first named dial, a rotary dial mounted upon said stationary dial, a sleeve carried by said rotary dial, a contact arm pivotally supported by said sleeve, a spring connected to said contact 70 arm for holding a portion thereof in engagement with any one of the segments of said first named dial, a slidable pin carried by said sleeve and adapted to engage said pivoted contact arm for moving it out of 75 engagement with any one of said segments, a bracket carried by said sleeve and extending through said first named dial, and an arm pivotally connected to the lower end of 80 said bracket.

In testimony whereof I affix my signature in presence of two witnesses.

CLARK J. WINSLOW.
